UNITED STATES PATENT OFFICE.

OLIVER H. P. GREEN AND DELOS CARPENTER, OF ORION, MICHIGAN.

LOCK.

SPECIFICATION forming part of Letters Patent No. 734,541, dated July 28, 1903.

Application filed February 10, 1903. Serial No. 142,722. (No model.)

To all whom it may concern:

Be it known that we, OLIVER H. P. GREEN and DELOS CARPENTER, citizens of the United States, residing at Orion, county of Oakland, 5 State of Michigan, have invented a certain new and useful Improvement in Locks, of which the following is a specification, reference being had to the accompanying drawings, which form a part of this specification.

Our invention has for its object novel locking mechanism, the same being more particularly designed and adapted as a keyboard-controlled lock for post-office boxes, although we do not limit our invention to any specific 10 use to which it may be applied, as we contemplate as coming within the scope of our invention any use to which the mechanism may be put. We will, however, describe the same as more specifically applied to a post-office box; and our invention consists of the construction, combination, and arrangement of devices hereinafter described and claimed, and illustrated in the accompanying drawings, in which—

Figure 1 is a view in side elevation, showing parts in vertical section. Fig. 2 is a view in side elevation from the side opposite that shown in Fig. 1, showing parts of the box in section. Fig. 3 is a view in cross-section on the line 3 3, Fig. 2. Fig. 4 is a detail view in vertical longitudinal section on the line 4 4, Fig. 7. Fig. 5 is a vertical cross-section on the line 5 5, Fig. 2. Fig. 6 is another detail view similar to Fig. 4 in vertical longitudinal section, showing features of our invention, the pinion on the shaft being out of mesh with the teeth of the swinging housing. Fig. 7 is an inverted plan view of portions of the lock mechanism with parts of the casing 30 or supporting-frame removed. Fig. 8 is a diagrammatic view illustrating means for operating the lock by a button on a keyboard. Fig. 9 is a view in front elevation of a post-office box to which our invention is applied. Fig. 10 is a view in vertical section through the box, showing the front of the box to which our invention is applied in rear elevation.

As applied to post-office boxes it is well-known that it is desirable for various reasons to have lock-boxes; but where lock-

boxes are employed it often occurs that the party renting the box has left or lost his key and he is therefore obliged to call upon the post-office employee to deliver to him the 55 contents of his box. Our invention aims to provide a box-lock of simple and economical construction and of superior utility whereby the lock is always under the ready and convenient control of the post-office official 60 and whereby the key may constantly remain in the lock, if preferred, or it may be removed therefrom, if desired, the key if remaining in the lock being secured against displacement by any party to whom it does 65 not belong, the lock being under the control of the postal official preferably by means of a button or analogous device upon a keyboard arranged in any convenient position—as, for example, within easy reach of the 70 livery-window.

While we have shown our invention as applied to a couple of boxes, the controlling mechanism of said boxes being led to or connected with a button on a keyboard, we would 75 have it definitely understood that the mechanism may be duplicated as may be desired, our invention contemplating as coming within its scope the equipment of all the boxes of a given office with our improved device, so 80 that, if desired, every box in the office is readily under the control of the postal official and without his being obliged to leave his place, he being enabled by means of our improved devices to open any given box that 85 may be desired, so that the party renting the box can have access to his mail therein. It will readily be seen that an office equipped with such mechanism will greatly facilitate the delivery of mail, will save labor, and at 90 the same time secure to every one renting a box absolute security of his mail. Our invention is of such a nature that a party wishing his mail need simply to give the number of his box to the postal official, whereupon the 95 said official can readily by means of his keyboard open the box of corresponding number, the buttons or keys upon the keyboard being numbered to correspond with the various boxes, respectively.

Our invention therefore is designed to provide a lock and a lock-box wherein the key

may or may not be removed therefrom, according to the wishes of the postal official and the party renting the box, the key being utilized or not, as may be preferred, the lock being, as above observed, always under the control of the postal official, if so desired.

We carry out our invention as follows: In the drawings, *a* represents a box, the same being provided with a door *b*, jointedly connected therewith, said door being controlled by our improved mechanism. The lock is provided with a support or framework, (indicated at *c*,) which is secured inside the box and preferably at one of the upper corners thereof above the swinging door. A key *d* is provided, having the outer end thereof, if retained in the lock, projecting through said supporting-frame and through the adjacent end of the box to the outside thereof. Within the casing or supporting-frame is a locking-bolt *e*, preferably made reciprocatory and which may be restored to normal position in any suitable manner, as by a spring *f*. Connected with said locking-bolt is a bell-crank lever *g*, suitably fulcrumed, as at *h*, in the supporting framework or casing, having one end thereof engaged with said locking-bolt in any suitable manner, the locking-bolt preferably being formed with an elongated orifice to receive the adjacent end of the bell-crank, so that the locking-bolt may have a movement independently of the bell-crank, if desired. The locking-bolt may be held in reciprocatory engagement with the casing in any suitable manner. With the opposite end of the bell-crank we connect an operating-rod or similar device *i*, by means of which when said operating-rod is actuated the bell-crank will be manipulated to disengage the locking-bolt. The bell-crank may be automatically restored to position in any suitable manner, as by a spring *j*. Within the casing *c* is a bracket *k*, within which is pivotally or jointedly engaged a swinging housing or stirrup *l*, provided with a keyhole-orifice *m* to register with the keyhole-orifice *n* in the case *c* when in proper position so to do, the swinging housing, however, being so constructed and arranged that the keyhole-orifice may be swung out of registerable position with the keyhole-orifice of the case, so that when so swung out of registerable position the key if in the lock cannot be removed therefrom or whereby if the key is out of the lock it cannot be engaged in the lock until said housing is swung into position so that its keyhole-orifice will register with the keyhole-orifice of the case by the postal official. One arm or side of said housing is toothed, as indicated at *p*. Within said inclosing case is also engaged a reciprocatory bar *q*, provided with a pinion *r* at one end thereof to engage with the toothed portion of the swinging housing when in position so to do and whereby when in such engagement the housing may be swung into and out of normal position, as may be desired. The bar or rod *q* is extended to the inner end

of the post-office box within reach of the postal official, so that he can move the same in or out readily, as may be desired, to engage its pinion with the toothed portion of the swinging housing or to disengage the pinion, as may be desired. Said bar and its pinion are constructed and arranged in such a manner that when the pinion is moved out of mesh with the toothed portion of the housing the key cannot unlock the locking-bolt. The locking-bolt is preferably provided with a spur or pin *s* to be engaged by the key when the key is free to operate to depress the locking-bolt. It will be seen, however, that when the rod and its pinion are moved out of mesh with the toothed portion of the housing it is projected into the path of the movement of the key toward said pinion or spur, so that the key cannot manipulate the locking-bolt. It will be evident that since the swinging housing is entirely under the control of the postal official by means of said bar *q* and its pinion the official has full control of the boxes, so that the key can neither be inserted or removed without his consent or without his attention. Neither can the party renting the box insert the key without the consent of the postal official, nor if the key were inserted could he actuate the lock without the consent of the official. It is apparent for like reasons that the lock can never be picked nor could it be manipulated even by a duplicate key. The rod connected with the bell-crank above mentioned is designed to be led to a keyboard or analogous device and connected with either a push or pull button by suitable intervening mechanism, so that by pushing or pulling the button the locking-bolt can readily be manipulated. The button mechanism connected with said rod may either be made single or double acting, as may be desired. In Fig. 8 we have shown single-acting mechanism consisting, essentially, of a bell-crank *u*, connected with a button *v* at one end and with said bar at the opposite end. In Fig. 8 also we have shown a double-acting mechanism wherein an additional lever *w* intervenes.

On the inner end of the box we preferably locate a dial *x*, the bar *q* being provided with an index-finger *y* to traverse said dial. Any suitable means may be employed to hold the index-finger in a given position on the dial, if desired.

The operation of our invention will now be understood, and it will be seen that various conditions may be secured thereby: First, the renter of the box may or may not take his key out of the box; second, his key may remain in the lock and cannot be removed therefrom except by the consent of the postal official; third, the key cannot unlock the box except by the consent and proper action of the postal official; fourth, the postal official may at all times unlock the box with or without the consent of the renter.

It will be seen that no man need to carry

his key unless he so desires and at the same time his mail may be under the control of the lock.

By providing all the boxes of a given office 5 with our improved mechanism the postal official can deliver to every one his mail by simply touching the proper button on the keyboard.

Should it be mutually agreed between the 10 renter and postal official, the key may of course be removed and the renter be privileged at any time to unlock his box without the intervention of the postal official. The 15 swinging housing has one of its arms fulcrummed upon a post or pin z , the key passing through the opposite arm of the housing, the housing swinging upon the key when in place.

It will readily be seen that this lock may be used also as a burglar-proof lock upon doors 20 and the like. Upon a door, for example, a party inside the room by simply pushing in the bar q to throw its pinion out of mesh with the swinging housing can prevent any possibility of a party unlocking the locking-bolt.

25 What we claim as our invention is—

1. A lock comprising a support or case open at its inner end and provided with a keyhole-orifice in its outer end, a locking-bolt to be operated by a key, additional means accessible 30 from the inner end of the case to actuate said bolt, a swinging stirrup within the casing provided with a keyhole in one side thereof registrable with the keyhole of the casing, and means to actuate said stirrup.

35 2. A lock comprising a support or case provided with a keyhole-orifice in the outer end or side thereof, a locking-bolt to be operated by a key inserted in said orifice, a swinging device provided with a keyhole registrable 40 with the keyhole of the casing, means accessible from the inner or opposite side of the casing to actuate said device, and additional means accessible from the inner side of the casing to actuate said locking-bolt.

45 3. A lock comprising a support or case provided with a keyhole-orifice, a locking-bolt to be actuated by a key, additional means to actuate said locking-bolt, controlling mechanism to control the removal or insertion of 50 the key provided with a keyhole registrable with the keyhole of the casing, and means of actuating said controlling mechanism.

55 4. A lock comprising a support or case provided with a keyhole-orifice in its outer end, a locking-bolt to be operated by a key, additional means extending through the inner end of the casing to actuate the locking-bolt, mechanism to control the removal or insertion of the key registrable with the key-hole of the casing, and means to control the 60 operation of said mechanism.

65 5. A lock comprising a support or case provided with a keyhole-orifice, a locking-bolt to be operated by a key, a swinging device provided with a keyhole registrable with the keyhole of the casing to control the removal or insertion of the key, a keyboard,

and means connected with the keyboard to actuate said locking-bolt.

6. A lock comprising a support or casing 70 provided with a keyhole-orifice in its outer end, a locking-bolt to be operated by a key, a bracket within the casing, a swinging device provided with a keyhole registrable with the keyhole of the casing housed within the 75 bracket, and means journaled in said bracket to actuate said device.

7. A lock comprising a support or casing provided with a keyhole, a locking-bolt to be actuated by a key, a swinging device to control the removal or insertion of the key provided with a keyhole registrable with the key-hole of the casing, and a shaft geared with 80 said swinging device to actuate said device.

8. A lock comprising a support or casing 85 provided with a keyhole, a locking-bolt to be actuated by a key, a swinging device to control the removal or insertion of the key provided with a keyhole registrable with the key-hole of the casing, a shaft geared with 90 said swinging device to actuate said device, and additional means to actuate said locking-bolt.

9. A lock comprising a support or casing 95 provided with a keyhole, a locking-bolt to be actuated by a key, a toothed swinging device provided with a keyhole registrable with the keyhole of the casing, a reciprocatory bar provided with a pinion registrable with the toothed portion of the said swinging device, 100 said bar arranged to move its pinion into and out of mesh with the toothed portion of the swinging device.

10. A lock comprising a support or casing provided with a keyhole, a locking-bolt to be 105 actuated by a key, a toothed swinging device provided with a keyhole registrable with the keyhole of the casing, a reciprocatory bar provided with a pinion registrable with the toothed portion of the said swinging device, 110 said bar arranged to move its pinion into and out of mesh with the toothed portion of the swinging device, said bar when moved out of toothed engagement with the swinging device moved into the path of the engagement 115 of the key with the locking-bolt.

11. A lock comprising a support or casing provided with a keyhole-orifice, a locking-bolt to be operated by a key, a bell-crank to actuate the locking-bolt, means to actuate 120 the bell-crank, a swinging stirrup within the case provided with a keyhole in one side thereof registrable with the keyhole of the casing, and means carried with the other arm of said stirrup to actuate the stirrup. 125

12. A lock comprising a support or casing provided with a keyhole, a locking-bolt to be actuated by a key, a toothed swinging device provided with a keyhole registrable with the keyhole of the casing, a reciprocatory bar 130 provided with a pinion registrable with the toothed portion of the said swinging device, said bar arranged to move its pinion into and out of mesh with the toothed portion of the

swinging device, said bar when moved out of toothed engagement with the swinging device preventing the turning of the key.

13. A lock comprising a support or casing 5 provided with a keyhole-orifice, a locking-bolt to be actuated by a key, controlling mechanism to control the removal or insertion of the key provided with a keyhole registrable with the keyhole of the casing, means to actuate said controlling mechanism, a push-button, and means connecting the push-button with the locking-bolt to actuate said locking-bolt.

14. A lock comprising a support or casing 15 provided with a keyhole-orifice, a locking-bolt to be actuated by a key, mechanism to

control the removal or insertion of the key provided with a keyhole registrable with the keyhole of the casing, means to actuate said controlling mechanism extending through 20 the inner end of the casing, a push-button, and means connecting the push-button with the locking-bolt to actuate said locking-bolt.

In testimony whereof we have signed this specification in the presence of two subscribers 25
